COMBINED SKEWER SET AND CUTTING BOARD RACK

Oliver M. Marcy, Webster Lake,
West Franklin, N.H. 03235

Filed Dec. 9, 1965, Ser. No. 134

Term of patent 14 years

(Cl. D44—1)

FIGURE 1 is a view in perspective of a combined skewer set and cutting board rack showing my new design.

The rear face, not shown, is plane and unornamented. I claim:

The ornamental design for a combined skewer set and cutting board rack, substantially as shown and described.
